GAME

Marvin H. Brook, Chicago, Ill.

Application May 18, 1936, Serial No. 80,373

7 Claims. (Cl. 273—89)

This invention relates to a game and more particularly to an improved baseball game.

One of the objects of my invention is to provide a baseball game in which the results or plays are determined by the skill of the participants.

Another object is to provide a game whereby the plays of the conventional baseball game are capable of being reproduced and are illuminated on a signaling indicator.

Another object is to provide an electrically controlled and operated signal system for a baseball game whereby the plays and combination of plays are signally illuminated.

Another object is to provide for a baseball game, an electrical circuit in connection with signal indicators, a switch, which when actuated, conditions or changes the circuit to the signal indicators for the purpose of illuminating other of the signals when the circuit is subsequently closed.

Another object is to provide a baseball game whereby the ball-receiving pockets are in electrical circuit with signaling indicators, and in which certain of said pockets are also in electrical circuit with a switch, which, when operated conditions the circuit to the signaling indicators to illuminate changed play results.

Another object is to provide for a baseball game an electrical circuit in connection with a switch which is adapted, when actuated, to change the circuit.

More specifically, I provide an electrical circuit in connection with a baseball game in which the metal ball when in any of the ball-receiving pockets, closes a circuit to illuminate on the signaling indicator the character of the play and a switch when operated to close the circuit to lamps for indicating base positions and outs, conditions or alters the circuit to the signaling indicator so that when the ball subsequently rests in certain of the receiving pockets, the signaling indicator will illuminate a changed condition of play.

Other objects will more presently appear as this description progresses.

Fig. 1 is a perspective view of my baseball game;

Fig. 2 is a bottom plan view of my game without the electrical connections;

Fig. 3 is a top plan view of one of the signaling indicators;

Fig. 4 is a cross section taken on the line 4—4 of Fig. 3;

Fig. 5 is an elevated view of my pitching mechanism;

Fig. 6 is a front view taken on line 6—6 of Fig. 5;

Fig. 7 is a side elevational view of the batting mechanism;

Fig. 8 is a cross sectional view of one of the fence pockets, taken on line 8—8 of Fig. 1;

Fig. 9 is a longitudinal cross sectional view of a fence pocket shown in Fig. 8;

Fig. 10 is a top plan view of the field box adjacent the pitching mound;

Fig. 11 is a cross sectional view of a field box taken on line 11—11 of Fig. 1;

Fig. 12 is a cross section taken on line 12—12 of Fig. 11;

Fig. 13 is an enlarged top plan of my switching mechanism;

Fig. 14 is a cross section taken on line 14—14 of Fig. 13;

Fig. 15 is a cross section taken on a longitudinal section 15—15 of Fig. 13;

Fig. 16 is a view of the electrical circuit.

Fig. 17 is a diagrammatic view of the field and the signaling devices and the various plays capable of being reproduced.

Referring to Fig. 1, I provide a supporting board 75 having upwardly projecting marginal walls 76 enclosing a playing field 77. The surface of the board is marked to simulate a conventional baseball diamond. Positioned on the field in positions approximating those assumed by players, I provide a plurality of fielders pockets or receptacles 25 lettered from A to K inclusive. Positioned along first and third base lines in foul territory I provide two additional pockets L and M. Adjacent the right and left field marginal walls I provide fence pockets numbered from 15 to 30, inclusive. 30

For indicating the plays I provide banks of indicating signals, indicated generally at 31 and 32, which are adapted to be illuminated as by the closing of an electrical circuit when the metal balls rest in any one of the fielder or fence pockets. 35

It will be noted that on each of the base positions, first, second and third, I provide signals 78, 79, and 80 which are provided with incandescent lamps 50, 51, and 52. These lamps are 40 in circuit with the fielders and fence pockets and with a manually operated switching unit which when actuated to close the circuit to any one or more of the base or out signals conditions or changes the circuit from its normal flow to a circuit which is adapted by the subsequent closing of contacts in the fielders and fence pockets to indicate other playing conditions on the indicating signals. All as more specifically explained in connection with the circuit diagram of Fig. 16 and 50 the diagrammatic view of Fig. 17.

Fielders pockets

Since the fielders pockets A to M are substantially the same, a description of one will be sufficient. Referring particularly to Figs. 11 to 13, it will be seen that in every position occupied by the fielders pockets I provide a cutout opening 81 in the supporting board 75. Adjacent the bottom thereof I provide a plurality of (five in most 55

instances) spaced V-notched metal strips 82 which are secured by nails 83 to the underside of the board 75. It will be understood that each of these strips have conducting wires leading therefrom in electrical circuit with the switching members and with the indicating members and with other metal strips in other pockets all as more clearly explained in connection with the wiring circuit. These strips are spaced from each other a distance apart so that any two can be bridged by a metal ball 84 to close the circuit to illuminate a respective signal on one or the other of the indicating members 31 and 32, and that by virtue of the V-shaped notches on the metal strips, the ball will assume a positive position of rest thereon to permit the circuit to be steadily closed. Adjacent the rear of each fielder's pocket I provide a back stop 85 in vertical alignment with the rear of the opening in the board and a forwardly projecting ledge 86 extending at right angles to the back stop 85. It will be understood that should the ball strike any one of these back stops, its continued movement will be arrested and it will drop within the pocket and come to rest on any two of the V-notched metal strips to close a circuit. As shown in Figs. 1, 11, and 12 each of the fielder's pockets from A to H, inclusive, have five metal strips or contact points, while pockets M and L have three metal strips or contact points. The outer pockets I and K on the pitcher's mound have three strips or contacts each, while pocket J has two contacts.

Fence pockets

35 Since the fence pockets numbered from 15 to 30, inclusive, are similarly constructed, a description of one will be sufficient. Adjacent each of the left and right field walls I provide in the supporting board 75, three longitudinal cut-out portions 90, 91 and 92. Secured to each of the left and right field marginal walls is a horizontally inwardly extending metal strip 93 which extends the combined length of the three cut-out portions.

40 Secured to the underside of the board 75 and spaced above strip 93, is a flexible metal strip 94 which forms the bottom of the fence pocket, but is adapted when depressed, as by the weight of the metal ball, to make contact with strip 93. Each of the strips 94 are of the length of the particular pocket and are in non-conducting relation with each other. These strips each have conducting wires leading therefrom in electrical circuit with the switch, and indicating signals, all as will presently be described. It is therefore seen that when the ball rests in a fence pocket, the circuit is adapted to be closed to indicate on one of the signal indicating members 31 and 32 the character of the play. As will be seen in Figs. 1 and 10 the longitudinal cut-outs are divided into separate pockets by partitioning members 95.

Signal indicating mechanism

45 Referring to the indicating signals 31 and 32 positioned along the first and third base foul lines and shown in Figs. 1, 2, 3 and 4, I provide rectangular cut-out portions in the supporting board 75 in which are adapted to be mounted the banks of signal lamps. Both of these banks of signals being similar in construction, a description of one will be sufficient. A plurality of sockets 97 which contain incandescent lamps, are adapted to be mounted on a support indicated at 98. The support is suitably secured to

the underside of the board 75 so that the lamps are positioned in the cut-out portion below the top of the board. Between each of the lamps is positioned a partition member 99. Extending over the cut-out opening and lying flush with the top of the supporting board 75 and secured thereto is a Celluloid or transparent covering 100. Secured to the underside of the Celluloid covering is a sheet 101 on which are printed various types of "plays" of the character more particularly shown in Fig. 17. It will be noted that over each such lamp, a different play is indicated, so that when any one particular lamp is illuminated the "play" inscribed directly over said lamp will be illuminated. Each of the lamps are in electrical circuit as will more presently be understood. Similarly mounted on the board at approximately center field position I provide a bank of 3 signal lamps to indicate the respective "outs". These lamps are likewise connected in circuit with the switch and with the pockets.

20 Each of the base signals 78, 79 and 80 have individual incandescent lamps which are also suitably mounted to the underside of the board in a manner similar to the other signal lamps.

Batting mechanism

25 Referring to Fig. 7, it will be seen that extending through the board 75, adjacent the batter's box is a vertical rotating post 105, which carries a horizontal member 106 and a depending arm 107 simulating a bat. The underside of the post carries a pinion 108 which is engaged by a rack 109, which is slidably supported on the underside of the board and which through connecting rods 35 is longitudinally movable to rotate the bat. The rack has secured at one of its ends a spring 110 which is anchored to board 75. To the other end of the rack I connect a rod 111 which is adapted to be actuated by a pivotally mounted lever 112 which is manually operated by a player. As the rack is moved the bat is rotated to intercept the ball as it comes from the pitching mound.

Pitching mechanism

30 The pitching mechanism shown in Figs. 5 and 6 comprises a pitching hammer 115, which projects through the opening provided in pocket J. The pitching hammer is pivotally connected at 116 to a rod 117. This rod has a step down connection 118 and a continuing rod 119 to which is secured a pivotably operated trigger lever 120. Secured to the lever 120 is a wire 121 which connects to one end of the pitching hammer 115. Supporting the rods 117 and 119 are U-shaped supports 122, and 123 which are secured to the underside of the board 75 and which pass through openings provided in the rods. The pitching unit including the hammer can thus be moved transversely to vary the angle at which it contacts the ball.

Switching unit

35 Referring to the mechanical structure of the switch shown in Figs. 13, 14 and 15, it will be seen that I provide an insulated support 125, on which are mounted four independently actuated switching members R, O, P and Q. In the support 125 I provide channelled recesses 126 in which are slidably mounted for longitudinal movement the insulated switch rods 127 to which at spaced intervals are secured metal contacts 128. Suitably secured and mounted on the board to be engaged by the movable metal contacts are stationary metal contacts 129. It will be understood that conducting wires lead from each of the mov- 75

able and stationary contacts and that as the switch rods are manually moved from one switch position to another, certain circuits are opened and others are closed, all as will be more fully understood in connection with the circuit diagram.

It will likewise be understood that other types of switching units can be used and I do not desire to be limited to the precise structural details of the switch as shown.

Electrical Diagram

Referring to the electrical diagram shown in Fig. 16, it will be seen that the conducting lines 13 and 14 are connected to the source of power 12. Tapped from line 13 and leading to each of the fence pockets 15 to 30 are conducting wires which are connected to contacts *b* of each pocket. Leading from contacts *a*, in pockets 15, 16, 17, 20, 22, 30, 29, 28, 25, 23, are conducting wires 56, 66, 67, 68, 69, 59, 60 each of which connects with a corresponding signal lamp in an individual circuit. The pair of contacts in each of said pockets are adapted to be closed (as by a ball) for the purpose of completing the circuit. By way of illustration, assuming contacts 15a and 15b or contacts 30a and 30b are closed, a current will continue to flow along a conductor 56 to illuminate lamp 48 and return through conductor 14. Connected from line 13 is a conductor 57 which connects with certain of the contacts shown in the field pockets A to M inclusive.

To permit a circuit to be made with these contacts, I connect contacts 1 and 5 of pockets A, B, C, D and contacts 3 in pockets E, F, G, H, and K and contact 1 in pocket I and contacts 1 and 3 in pockets L and M with conductor 58 which connects with lamp 33. The flow of current through the circuits described above which includes conductors 57 and 58 will not be affected by any subsequent manual movement of the switches O, P, Q and R indicated on the diagram and presently to be described, since they are not in circuit with them.

As shown in Fig. 16 the switches O, P, Q, R, are in normal or unmoved position, i. e., in a position before they are moved to illuminate any of the base position signal lamps 50, 51 and 52 or the out signals 53, 54, and 55. As each switch is moved other contacts are engaged to condition or change the circuit to the signalling indicators 31 and 32.

It will be seen that switches O, P, and Q are capable of only one switch change, while switch R can be moved to three different switch positions.

In switch R, contacts numbered 1, 5, 10, 15 and 20 are movable. In switches O and P contacts 1, 3, 6, 9 and 12 are movable. In switch Q contacts 1, 3, 6 and 9 are movable. The other remaining numbered contacts of each such switch would be the stationary contacts.

Referring to the fence pockets and more particularly to the pairs of contacts *a* and *b* of pockets 19, 21, 24 and 26, it is seen that when such circuits are closed, the current will flow from line 13 through conductor 59 through contacts 6 and 7 of switch O, through contacts 3 and 4 of switch P, to illuminate lamp 47 and back to line 14. In a similar manner, if pairs of contacts *a* and *b* of pockets 18 and 27 are closed, a current will flow from line 13 through conductor 60 through contacts 3 and 4 of switch O to illuminate lamp 45 and back to line 14.

If the switch O is moved, the circuits just described are altered, the current formerly flowing

through conductor 59 now continues through contacts 6 and 8 of switch O, through lamp 46 to illuminate it, and back to line 14. The current flowing through current conductor 60 now flows through contacts 3 and 5 of switch O through lamp 44 and returns to line 14. At the same time lamp 50 which is connected in series with contacts 1 and 2 of switch O is illuminated. If switch P is moved, lamp 51 is illuminated in a manner similar to that of lamp 50 and the current flowing through contacts 6 and 7 of switch O as described above now continues through contacts 3 and 5 of switch P and through lamp 49 to line 14.

Referring to the field pockets, when the contact 3 of pockets A, B, C and D are closed with contacts connected to conductor 57, a current will flow through conductor 61 through contacts 5 and 6 of switch R, through contacts 9 and 10 of switch Q, through lamp 33 to illuminate it and return to line 14.

If switch Q is moved, the current will flow through contacts 9 and 11 of switch Q, through lamp 36 to illuminate it and return to line 14. Lamp 52 will also be illuminated in a manner similar to that of lamp 50. When any of the contacts 1 of pockets E, F and K or contacts 5 of pockets G and H or contacts 3 of pocket I are closed with any of those connected to conductor 57, current will flow through conductor 62, through contacts 20 and 21 of switch R, through contacts 12 and 13 of switches O and P, through contacts 9 and 10 of switch Q to illuminate lamp 33. It will be noted that in the circuit just described, the switches are in a normal position, that is prior to being moved.

Assuming that switch R is moved to close the circuit between contacts 1 and 2 it will be seen that a circuit including lamp 53 is completed and the lamp will be illuminated. Since the contacts numerically following 6 of switch R with the exception of contacts 11 and 12 are connected in pairs, such as 6 and 7, 16 and 17, 21 and 22, those circuits which include conductor 61, 62 and 63 will not be changed unless switches O, P or Q are moved. With the switch R moved to the position just described, assume that switch O is moved to connect contacts 1 and 2. The current in conductor 61 will not be affected, but the circuit in conductor 63 will be changed to flow through contacts 15 and 17 of switch R, through contacts 9 and 11 of switch O, through contacts 10 and 12 of switch R to illuminate lamp 37. The current in conductor 62 will flow through contacts 20, 22 of switch R, through contacts 12 and 14 of switch O to illuminate lamp 34.

With switch O in moved position and switch R in normal (unmoved) position, the current in conductor 63 will pass through contacts 15 and 16 of switch R, through contacts 9 and 11 of switch O, through contacts 10 and 12 of switch R, through contacts 6 and 7 of switch P, through contacts 3 and 4 of switch Q to illuminate lamp 37. If switch P is moved, the flow of current is the same as above described with the exception that it now flows through contacts 6 and 8 of switch P to illuminate lamp 49.

When switch P is in its moved position and switches R and O in normal (unmoved) position, the current in conductor 63 flows through contacts 15 and 16 of switch R, through contacts 9 and 10 of switch O to contacts 9 and 11 of switch P to illuminate lamp 36. The current in conductor 62 flows through contacts 20 and 21 of switch R, through contacts 12 and 13 of switch

O, through contacts 12 and 14 of switch P to illuminate lamp 35.

- Referring to switch Q it will be noted that the circuit described included switch Q in normal or in unmoved position. With switch Q in moved position and switches R, O, P in normal (unmoved) position, the current passing through contacts 3 and 4 of switch Q will flow through contacts 3 and 5 to illuminate lamp 41. The current in conductor 63 will flow through switches R, O, P, through contacts 6 and 8 of switch Q, to illuminate lamp 39 and the current from conductor 61 will flow through contacts 9 and 11 of switch Q and illuminate lamp 36. If switch R is moved to its second movable position so that contacts 1 and 3 are engaged, it will be seen that lamp 54 is illuminated and that if any one of the circuits including conductors 61, 62 and 63 are closed, lamp 33 will be illuminated.
- I have described several combinations of positions of the switches. However, numerous other combinations are possible through different movement of the switches, but it is not believed necessary to describe such various combinations as they can be clearly understood from the electrical circuit.

On Fig. 17 I have shown a diagrammatic view of the top of the board showing the positions of the ball-receiving members, and the indicating signals with the inscriptions thereon. I will now describe the various plays and combinations of plays that can be made and which will be indicated on my game. For purposes of simplicity and clarification no electrical circuit is shown in this figure and suffice it to say that when the ball comes to rest in any one position in any of said pockets, an electrical circuit will be closed which will flash a corresponding lamp on the indicating signal banks 31 and 32. Also if players are positioned on base, or an out is to be indicated as is done by closing the switch circuits to the base or out lamps, the base and/or out signal lamps will be illuminated and the circuit will be reconditioned so that when the next play occurs the signal will flash to indicate a "hit" or "out", together with what position the base runner should next assume. The base position switch is then actuated to change the base indicating lamp to designate the changed condition as when a man advances from first to second, etc.

It will be noted that I provide four outfielder pockets such as a right fielder, right center fielder, left center fielder, and left fielder, their positions are indicated by letters A, B, C and D respectively. I also provide pockets representing a first baseman, shortstop, second baseman and third baseman, which I lettered E, F, G and H respectively. It will be seen that each one of these pockets have five points of contact which represent the five V-shaped metal segments in circuit with the switch and indicator, any two of which are adapted to be bridged as by a metal ball to close a circuit and illuminate a signal lamp to indicate a play. Thus in the pockets having 5 contacts, four separate circuits are capable of being closed and four different types of plays being made and flashed on the indicator. I have numbered each of these contacts from right to left 1 to 5, inclusive, so that I can best describe by referring to the numbers on the contacts what would be indicated when the ball bridges any such two contact points.

The pitcher's box is divided into three separate pockets, the outer two pockets each consisting of three contact points and the center one con-

sisting of two contact points. These pockets are lettered I, J and K, respectively. The pockets L and M each have three contact points.

Along the marginal walls on right and left fields I provide fence pockets which are likewise adapted to receive the ball. As shown on the drawings each of these pockets have two contact points in electrical circuit, which circuit is adapted to be closed when the ball falls therein. The first pocket along the left field outside of the third base line represents a foul ball, the other pockets are designated Home run, Double, Double, Single, Single, Single and Triple. The pockets along the right field are similarly marked.

Assuming that no men are positioned on base, and the ball falls into any one of the pockets, for example pocket 20, the signal on the indicator corresponding to the marking designated on the field margin will be flashed, in this case a single base hit. The ball is then removed from the pocket and the signal lamp is extinguished and the switch is manually actuated to close the circuit to light the lamp, indicating a runner on first base. This conditions the circuit so that when the next ball comes to rest in certain of the pockets, the signal indicator will indicate what position the man on base is to assume. As illustrated, if with a man positioned on first base the ball comes to rest in pockets 16 or 27 the indicator 31 will show that the play is a "double and the man on first scores". The switch to second base is then moved to indicate a man positioned on second base and the switch to first base is moved to open the circuit to extinguish the first base lamp. If the ball should rest in pockets 17 or 28 a "Double" would be indicated on signal lamps 30 and switches would be manually actuated to extinguish the 1st base indicating lamp and illuminate the 2nd base lamp. Assuming that the ball rests in either pockets 19 and 21, 24 and 26, and a man is positioned on first, the indicator will show that "man on base advances two bases" which will necessitate the operator extinguishing the first base signal lamp and actuating the switch to illuminate the third base lamp. If the ball should fall in any of the pockets as 15, 16, 17, 20, 22 or the similar corresponding pockets on right field border, the play flashed on the indicator will be the same with or without men positioned on base.

Following is a tabulated form of the various plays and combinations of plays that are capable of being made with my baseball game.

No outs, no one on base

Pockets	Contacts closed	Play	
A to M, inclusive	1-2; 2-3; 3-4; 4-5	Batter out.	60

No outs, man on 1st

Pockets	Contacts closed	Play	
A, B, C, D	1-2; 2-3; 3-4; 4-5	Batter out.	65

	G, H	4-5	Do.
	I	2-3	Do.
	K	1-2	Do.
	E, F	4-5	Batter and man on 3rd out. Do.
	G, H, J	1-2	Do.

15 One out, no one on base

	Pockets	Contacts closed	Play
	A to M, inclusive	1-2; 2-3; 3-4; 4-5	Batter out.

15

One out, man on first or first and second

	Pockets	Contacts closed	Play
	L, M	1-2; 2-3	Batter out.
	A, B, C, D	1-2; 2-3; 3-4; 4-5	Do.
	E, F, G, H	2-3; 3-4	Do.
	E, F	1-2	Batter out—man on 1st goes to 2nd. Do.
	G, H	4-5	Do.
	I	2-3	Do.
	K	1-2	Do.
	E, F	4-5	Batter and man on 1st out. Do.
	G, H, J	1-2	Do.

30

One out, man on 1st and 3rd or 1st, 2nd and 3rd

	Pockets	Contacts closed	Plays
	A to H	2-3; 3-4	Batter out.
	E, F	1-2	Batter out—man on 1st goes to 2nd. Do.
	G, H	4-5	Do.
	I	2-3	Do.
	L, M	1-2; 2-3	Do.
	K	1-2	Do.
	E, F	4-5	Batter and man on 1st out. Do.
	G, H, J	1-2	Do.
	A, B, C, D	1-2; 4-5	Batter out—man on 3rd goes home.

35

One out, man on second

	Pockets	Contacts closed	Plays
	A, B, C, D	1-2; 2-3; 3-4; 4-5	Batter out.
	E, F, G, H	2-3; 3-4	Do.
	I	1-2	Do.
	K	2-3	Do.
	L, M	1-2; 2-3	Do.
	E, F	1-2	Batter out—man on 2nd goes to 3rd. Do.
	G, H	4-5	Do.
	I	2-3	Do.
	K	1-2	Do.
	E, F	4-5	Batter and man on 2nd out. Do.
	G, H, J	1-2	Do.

60

One out, man on second and third

	Pockets	Contacts closed	Play
	A to H	2-3; 3-4	Batter out.
	I	1-2	Do.
	K	2-3	Do.
	L, M	1-2; 2-3	Do.
	E, F	1-2	Batter out—man on 2nd goes to 3rd. Do.
	G, H	4-5	Do.
	I	2-3	Do.
	K	1-2	Do.
	E, F	4-5	Batter and man on 2nd out. Do.
	G, H, J	1-2	Do.
	A, B, C, D	1-2; 4-5	Batter out—man on 3rd goes home.

75

One out, man on third

	Pockets	Contacts closed	Play
5	A to H.....	2-3; 3-4.....	Batter out.
	I.....	1-2.....	Do.
	K.....	2-3.....	Do.
	L, M.....	1-2; 2-3.....	Do.
	A, B, C, D.....	1-2; 4-5.....	Batter out—man on 3rd goes home.
	E, F.....	1-2.....	Do.
10	G, H.....	4-5.....	Do.
	I.....	2-3.....	Do.
	K.....	1-2.....	Do.
	L, F.....	4-5.....	Batter out—man on 3rd out.
	G, H, J.....	1-2.....	Do.

15 Two outs—all situations of men on bases

	Pockets	Contacts closed	Play
20	A to M, inclusive.....	1-2; 2-3; 3-4; 4-5.....	Batter out.

Man on first, or 1st and 2nd, or 1st and 3rd or 1st, 2nd, 3rd

	Pockets	Contacts closed	Play
25	Fence pockets 18, 26.....	a and b.....	Double man on 1st scores.
	Fence pockets 19, 21, 24, 26.....	a and b.....	Single man on 1st goes to 3rd.

30 Man on second or second and third

	Pockets	Contacts closed	Play
35	19, 21, 24, 26.....	a and b.....	Single man on 2nd scores.

It is seen that contacts of pockets 15, 16, 17, 20, 22 and 30, 29, 28, 25, 23 are directly connected to signal lamps which will glow when any one of the circuits is closed.

What I desire to secure by Letters Patents is:

1. In a baseball game apparatus including a ball made of conductive material, individual signal members, ball receiving pockets, each of said pockets provided with a plurality of pairs of segments, each of which pairs of segments are connected in electrical circuit to separate signal members, said segments being so positioned that a particular circuit may be closed by the ball in said pocket whereby a signal member will be actuated, a manually operated switch adapted to change the circuit from said pocket to said signal members so that other of said individual signal members will be actuated when said pocket circuit is subsequently closed.

2. In a baseball game apparatus including a ball made of conductive material, individual signal members, ball receiving pockets, each of said pockets provided with a plurality of separate pairs of contacts to be closed by the ball, each of said pairs of contacts connected in electrical circuit with different signal members, said contacts being so positioned that a particular circuit may be closed by the ball contacting each of said separate pairs of contacts in said pocket whereby a particular signalling member is actuated, a manually operated switch for changing the circuit so that if a circuit in said pocket is subsequently closed another signal member will be actuated.

70 3. In a baseball game apparatus including a

ball made of conductive material, individual signal members, ball receiving pockets, each of said pockets provided with a plurality of separate pairs of contacts to be closed by the ball, each of said pairs of contacts connected in electrical circuit with different signal members, said contacts being so positioned that a particular circuit may be closed by the ball in said pocket whereby a particular signalling member is actuated to indicate a particular play condition, a manually operated switch for changing the circuits so that if a circuit in said pocket is subsequently closed another signalling member will be actuated to indicate another play condition.

4. In a baseball game apparatus including a ball made of conductive material, individual signal lamps, ball receiving pockets, each of said pockets provided with a plurality of contacts in electrical circuit with a plurality of said signal lamps, said contacts being so positioned that a particular circuit may be closed by the ball in said pocket whereby certain of said signal lamps are operated, a manually operated switch to operate certain of said signal lamps and simultaneously change the circuit of said pockets so that upon a subsequent closing of said circuit by said ball a different signal lamp will be actuated.

5. In a baseball game apparatus, a playing field, a ball made of conductive material, individual signal indicating members, a plurality of ball receiving pockets positioned on said playing field, each of said pockets having a plurality of contacts in electrical circuits with said individual signal indicating members, said contacts being so positioned that a particular circuit may be closed by the ball in said pocket whereby different signal indicating members are operated when said ball closes the circuit in said pocket and a manually operated switch for changing said circuits from said pockets to said signal indicating members.

6. In a baseball game including a ball made of conductive material, a plurality of ball receiving pockets each having a plurality of contacts in electrical circuit with individual signal indicating members, said contacts being so positioned that a particular circuit may be closed by the ball in said receiving pocket whereby said signal members are operated, other signalling members for indicating players on base positions, said last mentioned signal members connected with said first mentioned circuits, a manually operable switch for operating said other signalling members and simultaneously changing said circuit to said play indicating members.

7. In a baseball game apparatus, including a ball made of conducting material, individual signal lamps, ball receiving pockets, each of said pockets provided with a plurality of pairs of contacts, each of said pairs of contacts connected in electrical circuit with different signal lamps and so positioned that a particular circuit may be closed by the ball in said pocket whereby different signalling members will be actuated, a manually operated switch comprising stationary contacts, and a slidale movable member to engage said stationary contacts so that the slidale movable member will change the circuit so that if a circuit in said pocket is subsequently closed another signal lamp will be actuated.

MARVIN H. BROOK.
